CAP FOR A PRESSURIZED CAN OR THE LIKE

Gary L. Kollberg, 1100 Parsippany Blvd.,
Parsippany, Troy Hills, N.J. 07054

Filed Apr. 2, 1968, Ser. No. 11,265

Term of patent 14 years

Int. Cl. D9—99

U.S. Cl. D9—258

FIG. 1 is a perspective view of a cap for a pressurized can or the like, showing my new design.

FIG. 2 is a top plan view;

FIG. 3 is an elevational view; and

FIG. 4 is a sectional view thereof taken on the line 4—4 of FIG. 2.

The broken line showings of a pressurized can in FIG. 1 and a portion of a pressurized can in FIG. 4 are for illustrative purposes only.

I claim:

The ornamental design for a cap for a pressurized can or the like, as shown and described.
